POURING SPOUT FOR TAPPING CONTAINERS

Manuel S. Lopes, Jr., Alameda, Calif.

Application March 18, 1939, Serial No. 262,659

10 Claims.

(Cl. 221—23)

This invention relates to devices by means of which sealed packages containing flowable material may be tapped and the material withdrawn therefrom and directed in a continuous stream into a receiving receptacle.

An object of the invention is to provide a pouring spout which may be inserted into a container through a wall thereof in such manner as to cleanly cut in the side wall an opening having a tab of complementary shape hinged to one side thereof, which tab, in the event that it is desired to withdraw the pouring spout from the container before the contents of the latter are entirely exhausted, may serve to close the opening and prevent dirt or other contaminating matter from entering the container, as well as to seal the container until such time as the pouring spout is replaced.

Another object of the invention is to provide in a device of the class described having a spout adapted to pierce the wall of a container, grip members which engage the interior surface of the said wall and a follower which engages the exterior surface of the container whereby said wall may be clamped therebetween and the spout firmly held in place.

The invention possesses other objects and features of advantage, some of which, together with the foregoing, will be specifically set forth in the detailed description of the invention hereunto annexed. It is to be understood that the invention is not to be limited to the specific form herein shown and described, since various other embodiments thereof may be employed within the scope of the appended claims.

With reference to the accompanying drawing:

Figure 1 is a top plan view of one form of pouring spout of my invention showing the spout attached to a sheet of material such as the side wall of a container, the said sheet of material being shown in section.

Figure 2 is a side elevational view of the structure shown in Figure 1.

Figure 3 is a side elevational view, partly in vertical section, of a modified form of pouring spout.

Figure 4 is a side elevational view of a paper container for liquids showing a still further modified form of pouring spot attached thereto. A portion of the view is omitted to shorten it.

Figure 5 is a top plan view of the pouring spout shown in Figure 4.

Figure 6 is a side elevational view of the structure shown in Figure 5.

Figure 7 is an end elevational view of the structure shown in Figure 6.

In broad terms, my invention comprises a tubular member adapted to be attached, preferably, to a fiberboard package containing pourable material so as to provide a pouring spot through which the material in the package may be dispensed. Cutting means is provided on the pouring spout so that, during the operation of pushing the spout against a surface of the package, an opening complementary to the cross-sectional form of the spout will be pierced through a wall of the package. Means is also provided on the spout which limits the amount of the package wall that the cutting means may sever so that a tab of the wall material is left hinged along a portion of the periphery of the opening and may be swung into the opening to close the latter upon removal of the spout. Yieldable means is provided on the spout for engaging one surface of the pierced wall of the package, and means preferably formed unitarily with the spout is provided for engaging, under force applied by said yieldable member, the opposite surface of the pierced wall of the package so that the said wall will be securely clamped to the pouring spout in such manner that they may not be easily separated.

In greater detail, my improved pouring spout may take a number of advantageous forms, one of which is illustrated in Figures 1 and 2 and comprises a unitary sheet of metal shaped to provide a generally cylindrical tubular spout body 8; the opposite end portions of the sheet which are brought into abutting relation along the line 9 being without curvature so that a chordal flat 11 is provided extending axially along, and preferably at the top of, the spout body. One end of the spout body is acutely inclined with respect to the axis of the body to provide sloping cutting edges 12 which meet diametrically opposite the line 9 in an extended and sharp cutting point 13.

When the pouring spout is positioned with the cutting point 13 engaging a surface of a sheet of material 14, representing a side wall of a preferably fiberboard package, and force is applied manually to the pouring spout, axially of the latter and in a direction perpendicular to the plane of the sheet 14, the cutting point 13 will pierce the sheet and, upon continued forcible advancement of the pouring spout, the cutting edges 12 will shear from the sheet a flap 16 which is complementary in form to the cross-sectional form of the pouring spout. This cutting of the

sheet 14 by the cutting edges 12 will cease, however, when the end 17 of the chordal flat 11 is reached thus providing at one side of the flap 16 an unsevered portion which serves as a hinge 18 for the flap.

It will be observed that by the provision of the hinge 18, the flap 16 may be caused to move into the opening pierced in the sheet 14 so as to close the opening against the passage therethrough of contaminating matter into the package should the pouring spout be removed before the contents of the package are completely dispensed.

Means is provided on the spout body 8 for gripping the package sheet 14 so as to join the spout body thereto. Spaced around the periphery of the spout body adjacent the cutting end thereof is one or more, three being the preferred number, of embossed protuberances 19 which slope, with respect to the axis of the spout body, outwardly from the said axis and away from the cutting end of the body and are each sheared, at their outer end, from the adjacent metal of the spout body to provide one or more pointed spurs 21. The radial extent of the spurs 21 is rather small, being in the order of $\frac{1}{2}$ of an inch. It will be seen that as the spout body is pushed axially through the opening cut in the package sheet 14, and the outwardly sloping protuberances 19 pass therethrough, the resilient fiberboard, of which the sheet 14 is composed, will be compressed and will, after the protuberances have passed completely through the opening, spring radially inwardly of the opening behind the projecting spurs 21. The slight radial projection of the protuberances allows the latter to pass through the opening without materially deforming the latter.

Means is provided engaging the surface of the package sheet opposite that engaged by the spurs 21 for forcibly urging the spurs against the package sheet so that the sharp ends of the spurs will become embedded in the sheet. Mounted on and for slidable movement axially of the spout body is a follower comprising a sleeve 22, surrounding the body, having a flange 23 formed integrally therewith and extending radially from the end thereof facing the package sheet. A coil spring 24, surrounding and concentric with the spout body, has one end bearing against the flange 23 of the follower and the other end engaging a collar 26 which is mounted on and concentric with the spout body in spaced relation to the follower and which is fixed against movement axially of the spout body by its engagement with a pair of spaced cylindrical hinge eyes 27 which are provided by tabs formed integrally with and extending from the end of the spout body. These hinge eyes provide journals for and engage hinge tabs 28 formed on and extending tangentially in opposite directions from the periphery of a circular flap 29 which serves as a pivoted closure for that end of the pouring spout which extends exteriorly of the package. It will be seen that the spring 24, in urging the follower against the exterior surface of the package sheet, will forcibly draw the sharp ends of the spurs 21 into engagement with the inner surface of the sheet causing the spur ends to bite into the sheet and thus firmly secure, against easy displacement, the pouring spout to the package.

In order to facilitate, as much as possible, the flow of material from the interior of the package into the inner end of the pouring spout, I provide one or more feed openings 31 in the inner end of the spout body.

In Figure 3 I have illustrated a materially simplified form of my invention. Here I replace the coil spring 24 with a collar 32 of resilient material, preferably sponge rubber, which is backed by a metallic washer 33 held against movement axially of the spout body by a plurality of protuberances 34 which are embossed radially outwardly from the metal of the spout body. The rubber washer, of course, functions in the manner of the spring, to forcibly press the spurs 21 against the surface of the package sheet.

In Figures 4 to 7 inclusive, I have shown a further modified form of my pouring spout particularly adapted to packages containing fluids. Referring to Figure 5, I provide a piece of sheet metal which may be rolled about a suitable mandrel so as to bring the opposite ends of the sheet into abutting relation along the line 36 to provide a tubular body 37 having at one end a piercing point 38 and inclined cutting edges 39, similar to the cutting end of the pouring spouts previously described, and one or more gripping spurs 41 also similar to those previously described. Disposed intermediate the ends of the body 37 are pairs of embossed protuberances 42 which extend radially outwardly from the periphery of the body and are spaced axially therealong so that a gap of predetermined width is provided between each pair of the protuberances.

A resilient follower is provided, comprising a substantially U-shaped member having a fixed leg 43, a movable leg 44, and an integral bridge portion 46 joining the legs together at one end. Both the fixed and movable legs are provided with alined apertures, the aperture 47 of the movable leg being slightly larger than that of the fixed leg so as to permit free movement of the spout body in the aperture as the leg 44 is moved. The aperture of the fixed leg, which is only sufficiently larger than the spout body so that the latter may slide therethrough, is provided with a pair of radially extending notches 48, see Figure 7, which are complementary in form with the protuberances 42 and which are positioned on a line exactly medially and longitudinally of the fixed leg 43. The U-shaped member is mounted on the body 37 by passing the body axially through the alined apertures and one of each pair of protuberances 42 through the notches 48 until the fixed leg 43 is positioned in the gap between the protuberances. The tube is then rotated through 180 degrees so that the protuberances will be finally located midway between the notches 48 and the leg 43 will thus be firmly secured to the spout body. The gap between the protuberances will, of course, have to be slightly less than the thickness of the sheet material from which the U-shaped member is constructed so that the resulting tight frictional engagement between the fixed leg and spout body will be sufficient to prevent easy rotational movement between the parts.

While the type of pouring spout just described may be used to dispense any kind of pourable material from packages which may be pierced by the spout, I intend it to be used in conjunction with the new types of fiberboard milk containers 49 one of which is shown in Figure 4. Since the advent of this type of milk container, users who have made a practice of removing the top cream from the milk find it quite difficult to now remove the cream. The factor contributing most to this situation is not so much the inability of the user to see the cream level in the new container as his inability to insert into the container the different types of stopples or baffles which have

long been on the market and were designed for use with the ordinary type of milk bottles. The last described form of my invention discounts this difficulty to a large extent. By inserting the pouring spout, as shown in Figure 4, where he believes the cream line should be, the user may drain most of the cream from the container without agitating the remainder of the milk and possibly diluting the cream. After serving as a cream extractor, the pouring spout may be left attached to the container to serve during subsequent pourings. When once in place the flexed resilient leg 44 securely clamps the container wall between such leg and the spurs 41 and functions to retain the spout firmly in position.

It will be observed that the pouring spout of my invention is constructed entirely without the use of solder. Thus the likelihood of tiny pieces of lead becoming mixed with the food is eliminated as is also the danger of the contents of the package becoming contaminated by contact with soldered joints that are usually provided in pouring spouts of this type.

I claim:

1. A pouring spout for attachment to packages of pourable material comprising a unit sheet of material formed to bring opposite edges thereof into abutting relation so as to provide a tubular member, said tubular member having the plane of one end thereof disposed angularly with respect to the central axis of the member so as to provide a cutter adapted to pierce, in a wall of said package, an opening complementary in form to the cross-sectional form of the tubular member and through which said member may be moved to enter said package, a plurality of protuberances formed by embossing radially outwardly, from the periphery of said tubular member, integral wall portions of said member and shearing each protuberance at one end from the main body of the member so as to provide at said end a sharp spur facing away from the cutting end of the member, said spurs, upon passage of said protuberances through the opening in the package wall formed by said cutter, being engageable with the inner surface of said package wall, a follower slidably mounted on said tubular member and engageable with the opposite exterior surface of the package wall, resilient means for urging the follower against said package wall so as to clamp said wall between the follower and said spurs, and means pivotally mounted at an end of said tubular member and forming a closure therefor.

2. A pouring spout for attachment to packages of pourable material comprising a unit sheet of material curved to bring opposite edges thereof into abutting relation so as to provide a cylindrical tubular member, said sheet of material having portions thereof paralleling said abutting edges uncurved so as to provide, on the periphery of the formed tubular member, a chordal flat area extending longitudinally of and entirely along said member, the plane of one end of said tubular member being inclined with respect to the axis of the latter, said plane intersecting said chordal flat area and sloping toward the end of the member to form at the said end a sharp cutting point, diametrically opposed to said chordal flat, and curved portions of the tubular member forming cutters extending from said point and terminating at the intersection of said plane with said chordal flat area, said point and cutters co-operating, when the tubular member is forcibly pressed axially and perpendicularly against the package wall, to cut in said wall a curved slit

complemental in contour with the contour of said curved portions forming the cutters and forming a flap in said package wall closing the opening in said wall bounded by said slit and hinged along one side of the opening by an uncut portion of the package wall complementary with said chordal flat and extending linearly between the opposite ends of said slit, means forming integral portions of said tubular element extending radially therefrom, passable through said opening and engageable with the interior surface of said package wall, and resilient means on said tubular member and positioned exteriorly of said package for urging said wall-engaging means into engagement with said wall.

15 3. A pouring spout for attachment to packages of pourable material comprising a unit sheet of material curved to bring opposite edges thereof into abutting relation so as to provide a cylind-

20 cylindrical tubular member, said sheet of material having portions thereof paralleling said abutting edges uncurved so as to provide, on the periphery of the formed tubular member, a chordal flat area extending longitudinally of and entirely

25 along said member, the plane of one end of said tubular member being inclined with respect to the axis of the latter, said plane intersecting said chordal flat area and sloping toward the end of the member to form at the said end a sharp cutting point disposed to cut the said flat area.

30 ting point, diametrically opposed to said chordal flat, and curved portions of the tubular member forming cutters extending from said point and terminating at the intersection of said plane with said chordal flat area, said point and cutters co-operating when the tubular member is forcibly

35 operating, when the tubular member is forcibly pressed axially and perpendicularly against the package wall, to cut in said wall a curved slit complementary in contour with the contour of said curved portions forming the cutters and forming
40 a flap in said package wall closing the opening in

40 said wall bounded by said slit and hinged along one side of the opening by an uncut portion of the package wall complementary with said chordal flat and extending linearly between the opposite ends of said slit, means forming integral portions

10 of said tubular element extending radially therefrom, passable through said opening and engageable with the interior surface of said package wall, a collar mounted concentrically on and
50 50 slidable along said tubular member, said slidable collar having a bore, a rib extending radially outwardly from the exterior surface of the collar, and a shoulder on the exterior surface of the collar.

collar having at one end thereof a radially extending flange for engaging the outer surface of said package wall, a fixed collar on and concentric with said tubular member and disposed in spaced relation to said slideable collar, a coil spring surrounding said tubular member and engaging

rounding said tubular member and engaging, at its respective ends, said fixed collar and the flange of said slid able collar, a pair of wings rising from an end of said tubular member and formed to provide tubular eyes engaging said fixed collar, and a closure flap covering an end of said tubular member and provided with tabs journaled in said eyes.

4. A pouring spout for attachment to packages of pourable material comprising a unit sheet of material formed to bring opposite edges thereof into abutting relation so as to provide a tubular member, said tubular member having the plane of one end thereof disposed angularly with respect to the central axis of the member so as to provide a cutter adapted to pierce, in a wall of said package, an opening complementary in form to the cross-sectional form of the tubular member and through which said member may be moved to enter said package, a plurality of pro-

tuberances formed by embossing radially outwardly, from the periphery of said tubular member, integral wall portions of said member and shearing each protuberance at one end from the main body of the member and along an undulating line so as to provide at said end of the protuberance one or more sharp spurs facing away from the cutting end of said tubular member, said spurs, upon passage of said protuberances through the opening in the package wall formed by said cutter, being engageable with the inner surface of said package wall, a follower slidably mounted on said tubular member and engageable with the opposite exterior surface of the package wall, resilient means on said tubular member and operatively connected with said follower for urging the latter against the package wall so as to clamp said wall between the follower and said spurs, and a flap pivotally mounted at an end of said tubular member and movable to close said end of the tubular member.

5. A pouring spout for attachment to packages of pourable material comprising a unit sheet of material formed to bring opposite edges thereof into abutting relation so as to provide a tubular member, said tubular member having the plane of one end thereof disposed angularly with respect to the central axis of the member so as to provide a cutter adapted to pierce, in a wall of said package, an opening complementary in form to the cross-sectional form of the tubular member and through which said member may be moved to enter said package, a plurality of protuberances formed by embossing radially outwardly, from the periphery of said tubular member, integral wall portions of said member and shearing each protuberance at one end from the main body of the member so as to provide at said end a sharp spur facing away from the cutting end of the member, said spurs, upon passage of said protuberances through the opening in the package wall formed by said cutter, being engageable with the inner surface of said package wall, and unit resilient means on said tubular member and engageable with the opposite exterior surface of the package wall for urging said spurs against the inner surface of said package wall.

6. A pouring spout for attachment to packages of pourable material comprising a unit sheet of material formed to bring opposite edges thereof into abutting relation so as to provide a tubular member, said tubular member having the plane of one end thereof disposed angularly with respect to the central axis of the member so as to provide a cutter adapted to pierce, in a wall of said package, an opening complementary in form to the cross-sectional form of the tubular member and through which said member may be moved to enter said package, a plurality of protuberances formed by embossing radially outwardly, from the periphery of said tubular member, integral wall portions of said member and shearing each protuberance at one end from the main body of the member so as to provide at said end a sharp spur facing away from the cutting end of the member, said spurs, upon passage of said protuberances through the opening in the package wall formed by said cutter, being engageable with the inner surface of said package wall, a washer of compressible material on said tubular member and engageable with the opposite exterior surface of the package wall, a rigid washer mounted on said tubular member and engaging said compressible washer, and means for con-

necting said tubular member and said rigid washer together against relative movement.

7. A pouring spout for attachment to packages of pourable material comprising a unit sheet of material formed to bring opposite edges thereof into abutting relation so as to provide a tubular member, said tubular member having the plane of one end thereof disposed angularly with respect to the central axis of the member so as to provide a cutter adapted to pierce, in a wall of said package, an opening complementary in form to the cross-sectional form of the tubular member and through which said member may be moved to enter said package, a plurality of protuberances formed by embossing radially outwardly, from the periphery of said tubular member, integral wall portions of said member and shearing each protuberance at one end from the main body of the member so as to provide at said end a sharp spur facing away from the cutting end of the member, said spurs, upon passage of said protuberances through the opening in the package wall formed by said cutter, being engageable with the inner surface of said package wall, and an integral resilient member having a fixed portion thereof secured to said tubular member and a movable portion thereof relatively movable with respect to said tubular member, said relatively movable portion being engageable with the exterior surface of said package wall.

8. A pouring spout for attachment to packages of pourable material comprising a unit sheet of material formed to bring opposite edges thereof into abutting relation so as to provide a tubular member, said tubular member having the plane of one end thereof disposed angularly with respect to the central axis of the member so as to provide a cutter adapted to pierce, in a wall of said package, an opening complementary in form to the cross-sectional form of the tubular member and through which said member may be moved to enter said package, a plurality of protuberances formed by embossing radially outwardly, from the periphery of said tubular member, integral wall portions of said member and shearing each protuberance at one end from the main body of the member so as to provide at said end a sharp spur facing away from the cutting end of the member, said spurs, upon passage of said protuberances through the opening in the package wall formed by said cutter, being engageable with the inner surface of said package wall, an integral piece of spring metal bent into substantially U-form and provided with a pair of substantially parallel legs, one of said legs having therein an aperture through which said tubular member is freely movable and which is adapted to engage the exterior surface of said package wall, and the other of said legs having therein an aperture through which said tubular member passes, means for securing said other of the legs to said tubular member comprising a pair of aligned and spaced protuberances extending radially from the periphery of said tubular member between which said other leg is positioned, and said aperture in said other leg having a notch extending radially therefrom through which said protuberances may pass.

9. A pouring spout for tapping a container comprising a cylindrical tube having a cutting end for piercing a wall of said container, a spur rising above the normal surface of said tube and having a relatively sharp point extending away from the cutting end of said tube for engaging the inner face of the pierced wall of said container, means slidably mounted on said tube for

engaging the outer face of said wall, and resilient means for urging said slidably means toward said spur to clamp said wall against the point thereof.

10. A pouring spout for tapping a container comprising a cylindrical tube having a cutting end for piercing a wall of said container, a spur rising above the normal surface of said tube and having a relatively sharp point extending away

from the cutting end of said tube for engaging the inner face of the pierced wall of said container, a washer slidably mounted on said tube and adapted for engagement with the outer face of said wall, and a spring disposed on said tube for resiliently urging said washer toward the point of said spur to clamp said wall thereagainst.
